The ornamental design for a tapered cup, as shown and described.

DESCRIPTION

FIG. 1 is a front perspective view of a first embodiment of a tapered cup, showing our new design;

FIG. 2 is a front elevation view thereof, the right, left and rear elevation views being the same as the front elevation view;

FIG. 3 is a top plan view thereof;

FIG. 4 is a bottom plan view thereof;

FIG. 5 is a cross-sectional view thereof, taken at line 5-5 of FIG. 1;

FIG. 6 is a front perspective view of a second embodiment of a tapered cup showing our new design;

FIG. 7 is a front elevation view of the tapered cup of FIG. 6, the right, left and rear elevation views being the same as the front elevation view;

FIG. 8 is a top plan view of the tapered cup of FIG. 6;

FIG. 9 is a bottom plan view of the tapered cup of FIG. 6;

FIG. 10 is a cross-sectional elevation view of the tapered cup of FIG. 6 taken at line 10-10 of FIG. 6;

FIG. 11 is a front perspective view of a third embodiment of a tapered cup, showing our new design;

FIG. 12 is a front elevation view of the tapered cup of FIG. 11, the right, left and rear elevation views being the same as the front elevation view;

FIG. 13 is a top plan view of the tapered cup of FIG. 11;

FIG. 14 is a bottom plan view of the tapered cup of FIG. 11;

FIG. 15 is a cross-sectional elevation view of the tapered cup of FIG. 11 taken at line 15-15 of FIG. 11;

FIG. 16 is a front perspective view of a fourth embodiment of a tapered cup, showing our new design;

FIG. 17 is a front elevation view of the tapered cup of FIG. 16, the right, left and rear elevation views being the same as the front elevation view;

FIG. 90 is a cross-sectional elevation view of the tapered cup of FIG. 86 taken at line 90-90 of FIG. 86.

The broken lines show portions of the tapered cup that form no part of the claimed design. The dashed and arrowed lines shown on either side of the perspective views show cross-sectional indicia and form no part of the claimed design.
